CLAIM

(52) **U.S. Cl.**

The ornamental design for a training apparatus, as shown and described.

USPC **D24/200**

DESCRIPTION

(58) **Field of Classification Search**

FIG. 1 is a perspective view of a training apparatus according to a first embodiment showing my new design;

USPC D24/171, 185, 186, 187, 188, 200, 201,
D24/206, 207, 209, 215; D29/101.3,
D29/101.5; D3/205, 299; D21/683;
128/95.1, 96.1, 99.1, 845, 846, 112.1;
602/2, 5, 6, 41; 607/1, 48

FIG. 2 is a front view thereof;

CPC ... A61N 1/04; A61N 1/06; A61N 1/18; A61N
1/26; A61N 1/36; A61N 1/0424; A61N

FIG. 3 is a rear view thereof;

FIG. 4 is a left side view thereof, a right side view being a mirror image;

FIG. 5 is a top view thereof;

FIG. 6 is a bottom view thereof; and

FIG. 7 is a perspective view of a training apparatus according to a second embodiment showing my new design;

FIG. 8 is a front view thereof;

FIG. 9 is a rear view thereof;

FIG. 10 is a left side view thereof, a right side view being a mirror image;

FIG. 11 is a top view thereof; and,

FIG. 12 is a bottom view thereof.

(Continued)

The broken lines shown on the drawings depict portions of the training apparatus that form no part of the claimed design.

The broken lines form no part of claimed design.

1 Claim, 6 Drawing Sheets
